UNITED STATES PATENT OFFICE.

FRANCIS H. BAINBRIDGE, OF CHICAGO, ILLINOIS.

DAM.

SPECIFICATION forming part of Letters Patent No. 537,520, dated April 16, 1895.

Application filed September 11, 1894. Serial No. 522,724. (No model.)

To all whom it may concern:

Be it known that I, FRANCIS H. BAINBRIDGE, of Chicago, Illinois, have invented certain new and useful Improvements in Dams, of 5 which the following is a specification.

The object of my invention is to provide a simple, economical and efficient metallic dam, especially adapted for use in closing valleys or canyons for the purpose of impounding 10 water; and the invention consists in the features and combinations hereinafter described and claimed.

In the accompanying drawings, Figure 1 is a vertical transverse section of my improved 15 dam; and Fig. 2 an enlarged annular section, taken in line 2 of Fig. 1 looking in the direction of the arrows.

In constructing my improved dam, I take a number of girders or trusses, A, preferably 20 formed of I-beams, and arrange them at the desired angle to the ground. In the drawings, it is about forty-five degrees, though this angle may be varied to suit special circumstances and conditions. I provide these girders 25 with a facing, B, formed of convex steel or iron plates—the convex sides arranged toward the body of the water—which are secured to the I-beams in any desirable manner, preferably by means of rivets. The arrangement of 30 these plates in a convex manner provides for the expansion and contraction of the dam in the direction of its length, so that there will be less danger of distortion or destruction of the dam, owing to different changes of temperature or pressure. The facing B I prefer 35 to make as above described of convex metallic sheets. I wish it understood, however, that these sheets are made of such a thickness as to be more or less elastic to permit of yielding so as to make up or compensate for the 40 expansion and contraction of the dam in the direction of its length. By making these sections elastic the plates can be made of any desired shape so that the dam in contracting 45 will tend to make them convex or irregular and in expanding will tend to make them flat.

To support these girders in their proper position, I provide a strut or series of struts, B, preferably formed of two sets of parallel 50 metallic beams, b, braced together in any convenient manner. When a series of struts is used, they are arranged at proper distances

apart, and each strut separates two or more girders, to which they may be and are preferably secured by means of bolts and nuts or 55 rivets. I leave between each set of struts a space, C, which permits of the expansion and contraction of the dam in its length. The side beams, b, as before stated, are preferably rigidly secured to the I-beam girders at their 60 upper ends, and have their lower ends resting on and anchored in pedestals, D, such pedestals being embedded the proper distance in the ground and forming a suitable resting place for the struts so that the danger of an 65 unequal sinking or yielding of the foundation upon which the dam rests is minimized. The side beams of the struts are preferably formed of I-beams, and are secured together at their 70 upper ends by means of the longitudinal I-beams, E, and angle plates, e, said longitudinal I-beams being also riveted to the I-beam girders for the purpose of obtaining a more perfect construction.

As before stated, the girders with their facing may occupy any suitable angle with reference to the ground or a horizontal plane; and in such instances the back struts will be arranged to occupy a suitable angle to take the pressure or stress from the facing directly 80 to the ground. The upper part of the beam is provided with a bracket, G, to which is nailed a suitable planking, g, which forms a walk across the deck, and adjacent to which is arranged a ground rail, g'. This walk may 85 be used for the inspection of the dam, or as a foot bridge when desired.

While I have described my invention with more or less minuteness as to detail, I do not desire to be limited thereto unduly, any more 90 than is pointed out in the claims. On the contrary, I contemplate all proper changes in form, construction and arrangement, the omission of parts and substitution of equivalents, as circumstances may suggest or necessity 95 render expedient.

I claim—

1. In a dam, the combination of metallic girders arranged parallel to each other and at an angle to a horizontal plane to support 100 a facing, a facing consisting of sections of elastic metallic sheets secured to the girders, and a series of struts arranged to support the girders in their proper position and permit

the expansion or contraction of the dam in its length, substantially as described.

2. In a dam, the combination of metallic girders arranged parallel to each other and at an angle to a horizontal plane to support a facing, a facing consisting of sections of curved metallic sheets secured to the girders, and a series of struts arranged to support the girders in their proper position and permit the expansion or contraction of the dam in its length, substantially as described.

3. In a dam, the combination of **I**-beam girders arranged parallel to each other and at an angle to a horizontal plane and forming the support for a facing, a facing consisting of sections of convex metallic sheets secured to the girders, and a series of metallic struts

secured to the girders and arranged to support them in their proper position, substantially as described.

4. In a dam, the combination of **I**-beam girders arranged parallel to each other and at an angle to a horizontal plane to support a facing, a facing of convex sections of sheet metal secured to the girders, and a strut or series of struts formed of two sets of **I**-beam side bars secured to each other and the girders, and arranged to support the girders and facing at the desired angle, substantially as described.

FRANCIS H. BAINBRIDGE.
